United States Patent Office

Des. 216,055
Patented Nov. 18, 1969

216,055

HOLDER FOR TOW ROPE

James F. Power, 603 Warren St., and John J. Kauffman,
907 Lincoln St., both of Chenoa, Ill. 61726, and
Charles M. Payne, 1504 E. Grove St., Bloomington,
Ill. 61701

Filed Oct. 15, 1968, Ser. No. 13,966

Term of patent 14 years

Int. Cl. D8—03

U.S. Cl. D71—1

Fig.2.

Fig.3.

Fig.1.

Fig.4.

Fig.5.

FIG. 1 is a side elevational view of one form of the holder for tow rope;

FIG. 2 is a top plan view thereof;

FIG. 3 is a bottom plan view thereof;

FIG. 4 is a fragmentary end elevational view thereof;

FIG. 5 is a view similar to FIG. 4 but showing the opposite end thereof;

FIG. 6 is a side elevational view of a modified form of a holder for tow rope;

FIG. 7 is a fragmentary end elevational view thereof;

FIG. 8 is a view similar to FIG. 7 but showing the opposite end thereof from that shown in FIG. 7;

FIG. 9 is a top plan view thereof; and

FIG. 10 is a bottom plan view thereof.

We claim:

The ornamental design for a holder for tow rope, as shown and described.
